UNITED STATES PATENT OFFICE.

WILLIAM MARTINEK AND HENRY J. HULSKER, OF INDIANAPOLIS, INDIANA.

CAR-DOOR.

SPECIFICATION forming part of Letters Patent No. 683,565, dated October 1, 1901.

Application filed May 14, 1901. Serial No. 60,226. (No model.)

To all whom it may concern:

Be it known that we, WILLIAM MARTINEK and HENRY J. HULSKER, citizens of the United States, residing at Indianapolis, in the county 5 of Marion and State of Indiana, have invented certain new and useful Improvements in Car-Doors; and we do hereby declare the following to be a full, clear, and exact description of the invention, such as will enable 10 others skilled in the art to which it appertains to make and use the same.

This invention relates to doors, and particularly to that class known as "sliding doors," for use on freight-cars.

15 The object of the invention is to produce a door which is slidable longitudinally of the car-body and in combination therewith novel mechanism for moving the door into the door-opening flush with the car sides.

20 Furthermore, the object of the invention is to produce a novel form of latch for retaining the mechanism in the position to which it is adjusted when the door is in place to close the opening.

25 Furthermore, the object of the invention is to provide novel means for directing the rear edge of the door in alinement with the car side and mechanism for swinging the front edge into the door-opening and retaining it 30 in said position.

Finally, the object of the invention is to produce a door and its operating mechanism which will possess advantages in points of efficiency, simplicity, and durability, proving 35 at the same time comparatively inexpensive.

In describing the invention in detail reference will be had to the accompanying drawings, forming part of this specification, wherein like characters denote corresponding parts 40 in the several views, and in which—

Figure 1 is a perspective view of a fragment of a freight-car body with the invention applied. Fig. 2 is a vertical sectional view in front of the operating-bar. Fig. 3 is a horizontal sectional view through the latch. Fig. 4 is a sectional view showing the rear hanger in detail. Fig. 5 is a view in elevation of the latch. Fig. 6 is a horizontal sectional view showing the latch, on an enlarged scale. Fig. 50 7 is a vertical section on line 7 7 of Fig. 5. Fig. 8 is a sectional view on line 8 8 of Fig. 1. Fig. 9 is a plan view of the track. Fig.

10 is a sectional view on the line x x of Fig. 1 with the operating-bar out of position for locking the door.

55

In the drawings, 1 indicates the track, which extends parallel to the car-body for a portion of its length and then approaches the said body. The car-door is supported by hangers 2 and 3, the latter of which travels 60 over the curved portion of the track and carries the rear edge of the door into the door-opening in line with the side of the car. A guide-plate 4 is secured along the edge of the door-opening to the post 4^a, and as the rear 65 edge of the door contacts with it said door is directed to its proper position. The rear edge of the door is beveled and sheathed by the metallic strip 5. The post 4^a is recessed and beveled at 4^b to correspond with the bevel of 70 the door with which it interlocks. The hanger 2 has pivoted to its lower end the upper end 6 of an operating-bar 28, said end being bent at right angles to the bar. The lower end 29 of the bar extends at right angles to the body 75 in an opposite direction to that of the upper end and is provided with a cross-pin 9, adapted to swing into the recess 10 in the car side back of the plate 11, said plate having lugs, back of which the cross-pin lies, to prevent 80 the outward movement of the lower end of the door when the mechanism is set to retain the door closed. The lower end of the operating-bar is recessed at 30 in order to pass the guide-bracket 31 on the side of the car when the 85 operating-bar is turned to the position shown in Fig. 10, when the door is free to travel. The operating-bar is partially rotated in any suitable bearings 12, secured to the car-door, and a collar is fastened to the operating-bar 90 and an arm 13 is pivoted to the collar for turning the operating-bar in its bearings.

When it is desired to open the door, the operating-bar is turned and the angular end is withdrawn from engagement with the plate. 95 At the same time the upper end is turned on the hanger and the forward end of the door is swung out of line with the side of the car and is free to move as the rollers 14 of the hangers travel on the track. The arm 13 100 also acts as a hasp, as it has a slot 16 for the reception of a staple 17, and the arm is retained in the staple by a pin 18. The outer end of the arm has secured thereto the mem-

bers 19 and 20 of a latch, which normally stand apart. A plate 21 is set in the car side and has an opening 22, into which the members of the latch are inserted when pressed together. When the latch members are in place, they are released, and, being free to resume their normally-separated position, spring back under the lugs 23 of the plate and can be released only by being pressed together out of engagement with the lugs.

The lower edge of the door is beveled, as shown at 24, and a plate 25 is secured on the outer surface and depends below the edge of the door.

15 A wear-plate 26 and a buffer-plate 27 are secured on the outer surface of the car, the former to protect the side of the car and the latter to limit the movement of the door in one direction.

20 Having thus described our invention, what we claim as new, and desire to secure by Letters Patent, is—

1. In a sliding door, a track having a curve at its rear end, hangers having wheels traveling on the tracks, an operating-rod having an angular end pivoted to the front hanger and an oppositely-disposed lower end, and adapted to lie in a recess in the car-body, when the door is closed, a cross-pin on the 30 lower end, a plate having lugs engaged by the cross-pin and means for manipulating the operating-rod.

2. In a sliding door, a track curved inwardly at its rear end, hangers having wheels 35 engaged by the track, a door having a beveled rear end, a guide projecting from the rear of the door-opening to engage and guide the door, an operating-rod on the outer surface of the door in the front, said operating-rod being pivoted to the lower end of the front 40 hangers and having an angular lower end adapted to enter a recess in the car-body, an arm secured to the operating-bar and a spring-

latch on the end of the arm substantially as described.

3. In a sliding door, a track having a curved rear end, hangers having wheels traveling on the track, an operating-rod having oppositely-bent ends, the upper end being pivoted to the front hanger and the lower end adapted to 50 engage a plate in the car-body for holding the door closed a hasp-like arm secured to the operating-rod and a spring-latch on the end of the arm substantially as described.

4. In a sliding door, a track having a curved 55 rear end, hangers having wheels traveling on the track, an operating-rod having oppositely-bent ends, the upper end being pivoted to the front hanger and the lower end adapted to 60 engage a plate in the car-body for holding the door closed, a hasp-like arm secured to the operating-rod and a spring-latch comprising two diverging members adapted to be pressed together, and a plate on the side of the car-body having a central opening and lugs under which the members are expanded when 65 released by the operator, substantially as described.

5. In a car-door, a door having a beveled rear edge, a door-post having a beveled surface to interlock with the rear surface of the door, a guide-bracket for the door, an operating-bar pivoted to the door for locking the same, said bar extending below the base of the door and engaging a locking-plate in the 75 car side, and being so shaped as to pass said bracket, hangers for the door, a track for the hangers and means for turning the operating-bar substantially as described.

In testimony whereof we affix our signatures in presence of two witnesses.

WILLIAM MARTINEK.
HENRY J. HULSKER.
